United States Patent Office

Des. 196,891
Patented Nov. 12, 1963

196,891

FIREPLACE SCREEN

George W. Henle, 13222 Manchester Road,
St. Louis 31, Mo.

Filed June 13, 1962, Ser. No. 70,525

Term of patent 14 years

(Cl. D81—5)

FIG. 1

FIG. 2

FIG. 3

FIG. 4

FIG. 5

FIG. 1 is a front elevational view of a fireplace screen, showing my new design;

FIG. 2 is a side elevational view thereof;

FIG. 3 is a rear elevational view thereof;

FIG. 4 is a top plan view thereof; and

FIG. 5 is a bottom plan view thereof.

I claim:

The ornamental design for a fireplace screen, as shown.
